(57) CLAIM

The ornamental design for a washing machine, as shown and described.

DESCRIPTION

FIG. 1 is a perspective view of a washing machine, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof; and,

FIG. 8 is an enlarged view of the portion 8 of FIG. 1.

The broken lines illustrating portions of a washing machine are environmental purposes only and form no part of the claimed design.

The dot-dash broken lines encircling enlargement portions of the design form no part of the claimed design.
